UNITED STATES PATENT OFFICE.

JULIUS BECKER, OF RACINE, WISCONSIN.

SINGLE-PHASE MOTOR.

1,269,152.

Specification of Letters Patent. Patented June 11, 1918.

Application filed August 24, 1914. Serial No. 858,228.

To all whom it may concern:

Be it known that I, JULIUS BECKER, a subject of the Confederation of Switzerland, and a resident of Racine, Racine county, 5 Wisconsin, have invented certain new and useful Improvements in Single-Phase Motors, of which the following is a specification.

The present invention relates to improvements in single-phase motors, and has for its main object the provision of a construction such that the motor will be self-starting—that is, will commence to operate upon the application of the single-phase current—10 and such that in the starting operation the motor will not draw an undesirably large current from the line. That is, one of the objects is to so construct the motor that in the starting operation the motor will not draw an excessively large current, or a current of volume approximating twice the normal full load. At the same time it is an object to so construct the motor that it will develop a large torque or turning effort 15 at the start. This feature is of peculiar desirability in a motor intended for use under conditions where the load is connected to the motor at the time the start is made, as, for example, in railway work.

Another object of the invention is to so construct the motor that it will have a better regulation than the single-phase motor of usual construction—that is, will not fall off excessively in speed between normal no- 20 load running speed and normal full-load running speed. One objection to single-phase motors of usual construction is that they fall off seriously in speed as the load comes on, and one of the objects of the present invention is to overcome this difficulty.

In connection with the foregoing objects it is also an object to so construct the motor that it will have a high power factor, so that the wattless current will not reach an ab- 25 normal figure. This has been a difficulty met with in most forms of single-phase motor heretofore developed and at times has been a very serious difficulty.

Still another object is to so construct the motor that the iron will be worked up to a high degree of usefulness, thereby increasing the weight efficiency, and permitting the motor to be made of comparatively small size and weight for a given output. One of the difficulties heretofore experienced in the 30 design and construction of single-phase mo-

tors has been that the iron could not be used to its full limit, and that therefore it has been necessary to make the field of greater size than is the case with polyphase motors. 60 This difficulty I have largely overcome in the present case in the manner to be presently described.

Still another object is to so construct the motor that it may be reversed at will, thereby permitting the operator to determine the direction of rotation at the start and to reverse the direction at will.

Other objects will appear from a detailed description of the invention, which consists 70 in the features of construction, and the combinations of parts hereinafter described and claimed.

Referring to the drawings:

Figure 1 shows diagrammatically a four 75 pole single-phase motor having applied thereto three short-circuited windings at various phase relationships or positions, each of said short-circuited or auxiliary windings being provided with a single turn, and 80 the stator being further provided with two sets of such auxiliary windings so that the direction of rotation can be controlled at will;

Fig. 2 shows an arrangement similar to 85 that of Fig. 1, with the exception that each coil of the auxiliary windings is provided with a plurality of turns, as might be the case, for example, when the construction were to be used in a motor of comparatively 90 large size;

Fig. 3 shows a section through one form of stator embodying the features of my invention, the auxiliary windings being placed in tunnels between the usual slots 95 which accommodate the power windings;

Fig. 4 shows a section similar to that of Fig. 3, with the exception that the tunnels for the accommodation of the auxiliary windings are elongated instead of being circular, so as to readily accommodate a plurality of individual conductors or turns as the case may be;

Fig. 5 shows an enlarged detail of the tunnel of the arrangement shown in Fig. 4, 105 the same being provided with a plurality of round conductors;

Fig. 6 shows a view similar to that of Fig. 5, with the exception that the tunnel is provided with a plurality of flat conductors;

Fig. 7 shows a view similar to that of

Figs. 3 and 4, the auxiliary windings in the present case being placed in the same slots or tunnels which accommodate the power windings;

5 Fig. 8 shows a view similar to that of Fig. 7, with the exception that in the present case the slots or tunnels which carry the auxiliary windings are placed closer together than those which do not carry such 10 windings;

Fig. 9 shows an enlarged view of one of the slots or tunnels of the arrangements shown in Figs. 7 and 8;

15 Fig. 10 shows an enlarged detail view of a desirable form of connection between the short-circuiting bar of the "squirrel-cage" rotor winding and the bar conductors of the same being taken on the line 10—10 of Fig. 7, looking in the direction of the arrows; 20 and

25 Fig. 11 shows diagrammatically the general relationships existing between the currents in the power and in the auxiliary windings, and shows how currents out of phase from the currents in the power coils are induced in the auxiliary windings, and how these currents which are out of phase from the main power current may be so related as to generate or produce a rotating 30 field, even during the starting operation.

35 In carrying into effect the features of the present invention, I prefer to mount or build windings on the stator or stationary element intermediate the power windings proper, which intermediate windings are so related to the power windings proper and to the rotating element or rotor, that they will have induced in them currents of phase relationship differing from, but bearing a desired 40 relationship to, the currents in the power windings proper. By so relating these auxiliary windings to the power windings, they will have generated in them currents of such phase relationship to those in the power windings proper that a rotating 45 magnetic field will be produced. Where in the specification and claims I use the term "power windings" or "power windings proper," it will be understood that I contemplate windings on the stator which carry the main current delivered from the line. Also where in the specification and claims I use the terms "auxiliary windings" or "short-circuited windings," it will be understood 50 that I contemplate the auxiliary windings to be presently described in detail, inasmuch as these auxiliary windings serve not only to provide the rotating field for starting purposes, but also serve to improve the normal 55 operations or running of the machine.

60 Referring now to the diagram shown in Fig. 1, the numeral 15 designates the power winding. In each of the several figures I have illustrated the features of my invention 65 as applied to a four-pole construction, but

it is manifest that they may also be applied to a construction including any number of poles. These four poles are designated by the numerals 16, 17, 18, and 19. Furthermore, I have illustrated the features of my 70 invention as applied to a motor, the stator of which is slotted as distinguished from a construction in which the magnetic poles are in the form of projections. The polar arc embraced by each of the poles in the arrangements shown in Figs. 1 and 2 is substantially 180 electrical degrees. On one side of each of these poles I provide one or more turns of auxiliary windings physically displaced from the magnetic center of the 80 pole so that there will be an electric displacement of the currents in said auxiliary windings. Also in each of the arrangements illustrated, I have provided three auxiliary windings at different amounts of electrical 85 and magnetic displacement from the power winding. In Fig. 1 these are designated by the numerals 20, 21, and 22. Each coil is provided with a single conductor adjacent to each coil of the power winding, and the 90 auxiliary coils, in effect, are in the form of wave windings. Each auxiliary winding constitutes a closed circuit, electrically distinct from the power winding and from the other auxiliary windings, so that the currents existing in the several auxiliary windings will be distinct and separate from each other, although related magnetically. 95

100 In the arrangement shown in Fig. 2, the auxiliary windings are designated by the numerals 23, 24, and 25. In this case each auxiliary winding is provided with two turns or conductors adjacent to each magnetic pole so that a greater magnetizing and inductive effect is secured than in the arrangement shown in Fig. 1.

105 In Figs. 3 to 9 inclusive, I have illustrated a number of constructions of stator embodying the features of invention herein disclosed, which figures will be presently described in detail. However, it will be understood at the present time that within the stator is mounted a rotor of suitable type of construction, as, for example, the "squirrel cage" type. In this type of rotor the conductor is short circuited and the alternating 110 magnetic field from the stator induces currents within the rotor windings, which currents are a function of the slip of the rotor and the frequency and voltage of the stator. 115

120 The currents existing in the rotor winding or conductors will lag somewhat more than 90 degrees behind the current existing in the stator power winding, depending, among other things, upon the reactance of the rotor squirrel-cage circuit.

125 The currents existing in the rotor conductors will, in turn, react upon the auxiliary windings and generate electromotive forces in the same. These electromotive 130

forces will be approximately 90 degrees behind the currents existing in the rotor conductors. However, there will also be a direct induction from the main or power winding into the auxiliary windings, the electromotive force of which will lag behind the current existing in the main power winding an amount depending upon the several reactances of the circuits, and the amount of 10 mechanical displacement of each auxiliary winding with respect to the power winding. This "direct" component of electromotive force will act with the component generated by the currents in the rotor, so that 15 the net electromotive force in each auxiliary winding will be resultant of two components.

Referring to Fig. 11, I have plotted diagrammatically curves showing in a general 20 way the currents and electromotive forces existing in the main power winding, the rotor conductors, and one of the auxiliary windings. In this case the current in the main power winding is designated by the numeral 25^A. This current induces an electromotive force in the rotor conductors, which electromotive force lags approximately 90 degrees behind the current in the main power winding. This electromotive force is 25 indicated by the curve 26. Owing to the reactance of the rotor electric circuit the current in the rotor conductors will lag behind the electromotive force in said conductors and may be indicated by the curve 30 27. Considering one of the auxiliary windings, and preferably considering the more simple arrangement illustrated in Fig. 1, in which each coil of said winding is provided with a single turn, there will be introduced in said winding a component of electromotive force by the current in the rotor conductors and which is indicated by the curve 27. This component of electromotive force will lag behind the current in the rotor 40 and may be indicated by the curve 28. Owing to the self-induction of the rotor conductors which produces the lag between curves 26 and 27, the component of electromotive force 28 will be considerably more 45 than 180 degrees behind the current in the main power winding.

The component of electromotive force generated in the auxiliary winding by direct influence from the main power winding will 50 lag behind the current existing in the power winding an amount dependent, among other things, upon the mechanical displacement of the auxiliary winding under consideration, from the power winding, and may be 55 designated by the curve 29 of Fig. 11. Obviously the net electromotive force existing in the auxiliary winding which is available for the generation of current therein will be 60 the resultant of electromotive forces represented by the curves 28 and 29 and which 65

may be designed by the curve 30 of Fig. 11. The position of this curve with respect to the curve 25^A which indicates the current in the main power winding will depend upon the relative positions of the two curves 28 70 and 29, as well as their proportionate magnitudes. The current in the auxiliary winding, of course, will lag behind the resultant electromotive force existing in it and may be 75 designated by the curve 31.

The foregoing analysis does not take definite account of the displacement of the auxiliary winding with respect to the main power winding along the face of the field magnet of the stator, and does not take into account the relative reactions between a plurality of separate sets of auxiliary windings, such as are shown in each of the several figures. These relative inter reactions are such that the phase relationships of the various 80 auxiliary currents differ with respect to the current in the main power winding; thus auxiliary windings which lie with their turns closest to the centers of the power coils differ in phase relationship from the current in the main power coils by an amount different from those currents in the remaining auxiliary windings. It is, therefore 85 found by actual experience that a true rotating field is produced in the stator so that the turning effort exerted on the rotor is substantially the same as that which is exerted on the rotor of a polyphase machine. The direction of this turning effort depends upon the relative positions of the auxiliary coils 90 to one side or the other of the main power winding. It, therefore, follows that the direction or rotation both at the start and under normal running conditions can be controlled or determined by the location of the 95 auxiliary windings. For example, in Fig. 1, I have illustrated by means of the lines 31^A, 32 and 33 a second set of auxiliary coils or windings which may be brought into action, if desired, by suitably connecting them and 100 disconnecting the remaining coils. By so 105 doing the motor may be made reversible at will.

In the arrangement shown in Fig. 3 the auxiliary turns are accommodated in tunnels 115 34 formed in the teeth between the power slots, the teeth being of uniform width throughout the entire periphery of the stator. This construction is suitable for use where each coil of the auxiliary winding constitutes a single turn. In the arrangements shown in Fig. 4, the auxiliary turns are accommodated in tunnels 35 also formed in the teeth between the adjacent power windings. This construction is suitable 120 for use where each coil of the auxiliary winding consists of a plurality of turns either in the form of circular wires or bars 36, as shown in Fig. 5, or in the form of flat strips 37, as shown in Fig. 6. 125 130

In some cases, it would be desirable to place the turns of the auxiliary windings in the same slots as those which accommodate the main power windings, and such arrangements are shown in Figs. 7, 8 and 9. In the arrangement shown in Fig. 7, all of the slots are of uniform width and the teeth between them are also of uniform width. The turns of the power winding are laid in the bottom portions of the slots, whereas the turns of the auxiliary windings are laid in the top portions of the slots.

In the arrangement shown in Fig. 8, the teeth 39 between those slots which accommodate the auxiliary windings are made of less width than the teeth 40 between those slots which do not accommodate the power windings. This arrangement is in general preferable to that in which all of the teeth are of uniform width for the reason that the existence of the currents into the auxiliary windings will modify or change the magnetic distribution so that a better operation and performance of the motor will be secured than where the teeth are all of uniform width. It will be noted in this connection that, in the arrangement shown in Figs. 3 and 4, the provision of individual tunnels for the accommodation of the auxiliary windings will, in itself, cut down the amount of metal in the teeth in which these tunnels are formed, so that the net result in this case is similar to that of the arrangement shown in Fig. 8.

It was previously shown that the resultant electromotive forces existing in the several auxiliary windings are functions of electromotive forces induced directly from the main power winding and from the currents existing in the rotor. In some forms of construction it may be desirable to eliminate to a greater or less extent the one or the other of these influences, and, therefore, in Fig. 9 I have illustrated a magnetic shield or the like 41 interposed between the turns of the main power winding and those of the auxiliary winding. This arrangement may be particularly desirable for use in those constructions wherein the turns of the auxiliary winding are laid in the same slots with the turns of the main power winding. Ordinarily such a magnetic shield may take the form of a layer of magnetic steel laid between the windings, or it might take the form of an iron bridge separating two individual tunnels or slots in which the turns of the two windings are laid.

In Fig. 10, I have shown a suitable form of connection between the ends 42 of the bars of the squirrel cage and the encircling bar 43 which joins together all of said bars and short circuits them. In this case, the bars 42 are flat and lie radially in the rotor, so that the rotation of the same will generate air currents for the purpose of cooling

the machine to a greater extent than would otherwise be secured.

It will frequently be found necessary to limit the volume of current flowing in the auxiliary windings. This can be done by making said windings from a comparatively high resistance material, such as iron or steel, or a suitable alloy, or the conductors lying in the tunnels or slots may be of copper with one or more sections of resistance material inserted in the circuit at a suitable point. It may, however, be desirable to form the auxiliary windings of iron or steel, or other magnetic material, so as to make the magnetic conductivity as high as possible.

Experience has shown that it is preferable to use a plurality of sets of auxiliary windings, and ordinarily three sets of such windings will be found to give the best results. However, the exact number to be used in any given case will depend upon the various other factors entering into the motor construction, its size, frequency of the current on which it is to be used, etc.

Machines embodying the features of invention herein disclosed will be found to have an unusually large torque at starting closely resembling a polyphase motor in this regard. Furthermore, the starting current, while generally larger than the corresponding running current, will not exceed the same by an undesirable large amount. Another feature which is disclosed in machines of this type is that they have an unusually good regulation; that is to say the change of speed between no load and full load is relatively small.

I claim:

1. In a single-phase motor, the combination with a stator field core, of conductors of a power winding embedded therein, connections between said conductors for providing turns of power winding in the field core suitably positioned therein for the generation of alternate north and south magnetic poles along the face of the field core when the power winding is energized, groups of auxiliary turns in the core intermediate turns of the power winding, each of said groups of auxiliary turns being suitably connected up to provide auxiliary sets of coils in the core displaced along the body thereof with respect to the coils of the power winding, and each of said sets of auxiliary coils having a different amount of displacement with respect to the power winding from the other sets of auxiliary coils, and a rotor mounted within the stator core.

2. In a single-phase motor, the combination with a stator field core, of a plurality of power coils embedded in the same and adapted to generate alternate north and south poles in the core, and a group of auxiliary coils corresponding to each of the power

coils, the auxiliary coils of each group being angularly displaced from corresponding power coils different angular amounts, and the auxiliary coils of the various groups 5 being connected up in sets, the auxiliary coils of each set being displaced from their respective power coils by equal angular amounts, for the purpose specified.

3. In a single phase motor, the combination of a stator field core of a plurality of 10 power coils embedded in the same and adapted to generate alternate north and south poles in the core, and a group of auxiliary turns on each side of each power coil, the 15 auxiliary turns of each group being angu-

larly displaced from their respective power coils different angular amounts, each auxiliary turn of each group being angularly displaced from its power coil an amount equal to the angular displacement of a 20 corresponding turn of a group adjacent to each of the other power coils, and means for connecting in series corresponding auxiliary turns of the several groups, for the purpose specified.

JULIUS BECKER.
